UNITED STATES PATENT OFFICE.

VILLA WILKERSON, OF NIOTAZE, KANSAS.

WIRE-SPOOLING MACHINE.

SPECIFICATION forming part of Letters Patent No. 650,887, dated June 5, 1900.

Application filed June 1, 1899. Serial No. 718,997. (No model.)

To all whom it may concern:

Be it known that I, VILLA WILKERSON, a citizen of the United States, residing at Niota-
ze, in the county of Chautauqua and State
5 of Kansas, have invented certain new and useful Improvements in Wire - Spooling Ma-
chines; and I do declare the following to be a full, clear, and exact description of the inven-
10 tion, such as will enable others skilled in the art to which it appertains to make and use the same, reference being had to the accompanying drawings, and to the letters and figures of reference marked thereon, which form a part of this specification.

15 My invention is a device for spooling wire, cord, and the like, and is so constructed that it may spool wire, cord, and the like of different sizes and fill spools of different lengths and sizes.

20 In the accompanying drawings, Figure 1 is a perspective view of my invention. Fig. 2 is a front view with the device for carrying the wire cut away on the line *a a* of Fig. 1. Fig. 3 is a rear end view. Fig. 4 is a longitudinal central sectional view. Fig. 5 is an elevation of the device for regulating the tension of the wire. Fig. 6 is an edge view of the wheel *b* shown in Fig. 4, and shows more clearly the relative sizes of its cogs. Figs. 7, 8, 30 and 9 are detail views.

In the accompanying drawings, 1 represents the base of the framework.

2 represents an upright which holds the tension-rolls that carry the wire to the spool-
35 ing-guide.

3 represents uprights in which are journaled the cog-wheels and worm-shaft.

4 is a support of the guide.

Journalized in the uprights 3 is a shaft 5, car-
40 rying on it a sleeve-worm 6, adapted to be se-
cured in place by a screw 7. The said shaft 5 may carry finer or coarser worms, so as to enable said shaft to be geared with either the central row of cogs *e* or the side rows *e' e''* of the wheel *b*, so as to provide means for giving a different relative speed to the two shafts 5 and 27. On one end of this shaft is secured a spool 8. This end of the shaft may carry larger or smaller spools, as this machine is adapted to spool fine or coarse wire. It may spool several grades of wire. On the other end of this shaft is secured a cog-pinion 9,

that meshes with a large driving cog-wheel 10, journaled between the posts 3 and the bearing $3\frac{1}{2}$.

On the rear end of the base 1 is erected an upright 11, and on the upper end of this upright is a movable bearing 12, and in this bearing is a shaft 13, provided with a longitudinal groove 14. Said shaft has on its outer end a headpiece 15, and said shaft is adapted to be moved back and forth in the opening in which it works, and when fixed in the position desired it may be held in place by a thumb-screw 16. Near the inner end of this shaft is a flange 17, against which works one face of a triple cog-wheel *a b c*. The other face of said cog-wheel works against a securing-pin 18. These three wheels *a b c* are secured together by screws *X* and may be raised or lowered by moving the bearing 12 up or down and securing it by the screw 19, which passes through plate 20' into the perforation 20" of the bearing 12. Each wheel or row of cogs will spool three sizes of wire.

The upright 11 is provided with a vertical slot 20, in which works one end of a U-shaped bearing 21, the other end of which bearing works in a slot 20' of an opposite upright 22. This bearing 21 is provided with a central 80 opening 23, in which works the neck end of a screw 24, the lower end of which is threaded and turns up and down in a threaded opening 25 in the base-frame of the machine. In the perforated ends 26 of said bearing 21 is 85 journaled a shaft 27, on which is secured a triple cog-wheel *c' b' a'*. Instead of three there may be five wheels on shaft 13 and five wheels on shaft 27. I have, however, shown only one sleeve-worm on shaft 5 and three wheels on each of the shafts 13 and 27, as I deemed them sufficient to illustrate my invention, the upper wheel being shifted, as above described, to mesh with the lower wheel.

The triple wheel *a' b' c'* cannot be moved to the right or left, but only up and down, as above described.

The triple wheel *a b c* may be moved to the right and left and up and down by the means above described. The center *b* of the triple wheel *a b c* is provided with a central row of cogs, as shown in the several figures of the drawings; but in addition to its central row

of cogs e it is provided on each side with a side row of cogs e' and e^2 . (See Fig. 6.) The side row of cogs e' are larger and wider apart than the cogs in row e^2 , and in the central row

- 5 e the cogs are larger and wider apart than either of the other two rows, (see Fig. 6,) and therefore when said cogs e' are meshed with a corresponding worm-sleeve we get greater speed of said shaft than when the proper 10 worm-sleeve is meshed with cogs e^2 , and when cogs e are meshed with a corresponding sleeve we get greater speed than when meshed with either of the other two.

When I desire to mesh wheels a and a' , I 15 slip the shaft 13 to the left. When I wish to mesh wheels b and b' , I shift the shaft until wheel b is just above the wheel b' . When I wish to mesh the wheels c and c' , I shift the shaft 13 to the right until the wheel c is immediately over the wheel c' , and in every case 20 I bring the wheels in contact by turning the screw 24. When the wheels a and a' are meshed, the worm runs in the side cogs e' , and when the wheels c and c' are meshed the 25 worm runs in the side cogs e^2 , and when the wheels b and b' are meshed the worm runs in the central cogs e .

On one end of the shaft 27 is secured a heart-shaped wheel 28, having in its periphery a 30 groove 29 and a slot 30.

To the base of the machine is pivoted the lower end of a guide 31, having in its center a slot 32 and in its upper end a slot 33. In the slot 32 is secured an arm 34, and to the 35 end of said arm is journaled a wheel 35, which runs in the groove 29 of the heart-shaped wheel 28. This arm 34 may be moved in or out in the slot 32 and the wheel 28 may be more or less eccentrically secured on the shaft 40. 27. When secured near its center, it winds the wire on a short spool. When it is eccentrically secured on the shaft, it winds a long spool, and whether it is secured eccentrically or concentrically the arm 34 must be moved in or out accordingly to meet the requirements of 45 such conditions. As the heart-shaped wheel 28 moves around it moves the upper end of the guide to the left, and the coil-spring 36 draws it to the right. Thus it is alternately moved to 50 the right and left. The wire runs between the rollers 37 and 38 in the upright 2, and thence through the slot 33 in the guide 31. Thus the wire is wound on the spool back and forth from one end to the other.

55 The thumb-screw X is to regulate the tension of the wire. The wheel 35 is made to hug the periphery of the heart-shaped wheel 28 by means of a spring 36, and the guide is kept in an upright position by means of a 60 headed bolt $37\frac{1}{2}$, which works in a slot 39 of the support 4.

The heart-wheel 28 will spool a two-inch spool and can be made to spool a shorter spool by setting it in from the heel, and by 65 setting it toward the heel it will spool a longer spool.

It will be seen that I can spool a short spool

and spool longer and longer, as desired, within the capacity of the machine—that is to say, I am not confined to any particular length of 70 spool inside the capacity of the machine.

This machine as constructed will spool nine sizes of wire, each one below and one above any given number—that is to say, if geared to spool a wire No. 16 it will also spool Nos. 75 18 and 14, if set to spool a wire No. 24 it will also spool Nos. 26 and 20, and if set to spool a wire No. 30 it will also spool wires Nos. 28 and 32, and so on.

To adapt this machine for factory work, 80 we may remove the crank-arm $39\frac{1}{2}$ and in lieu thereof put on a band or cog wheel.

In addition to being able to secure the heart-shaped wheel 28 to the shaft 27 more or less eccentrically by means of the slot 30 we may 85 use a larger or smaller heart-shaped wheel, thus enabling my machine to spool a greater number of sizes of wire and of turning out a greater number of different-sized spools.

On one end of the base and on a line with 90 the guide 31 and spool 8 is erected an upright 2, having arms 2'. Over the top of these two arms is secured a cap 2''. These two arms have internal vertical slots 2'''. Journaled in the lower ends of the slots 2''' is a wheel 95 37, provided in its center with an annular groove 40 for wire to run in and on each end with a flange 41. Just above this wheel 37 and working in slots 2''' are two bearings 42, and in these two bearings 42 is journaled a 100 roller 38, shortened to work between the flanges 41 of the spool 37 and keep the wire down in the groove 40. Working in said slots 2''' is a plate 44, and between each end of this plate and the bearings 42 are spiral springs 105 43, which press bearings 42 down, and consequently the roller 38 down.

Having described my invention, what I 110 claim as new, and desire to secure by Letters Patent, is—

1. A wire-spooling machine, consisting of the base 1, and uprights 3 and support 4; shaft 5, journaled in uprights 3; sleeve-worm 6, secured on said shaft and adapted to mesh with wheel b , of triple wheel a, b, c ; spool 8, secured on one end of shaft 5, and cog-pinion 9, secured on the other end of said shaft; bearing 11, rising from the base and having slot 20; movable bearing 12, secured to the upper end of upright 11; shaft 13 secured to 120 said bearing; triple wheel a, b, c , journaled on the inner end of shaft 13; shaft 27, journaled in U-shaped bearing 21, adjustably secured in slots 20, and 20', of uprights 11, and 22; grooved and slotted heart-shaped wheel 125 28, secured on one end of shaft 27; guide 31, having slots 32 and 33, secured to the base; arm 34, adjustably secured to slot 32, and bearing in one end a wheel 35, adapted to run in groove 29, of wheel 28, and coil-spring 130 36, adapted to cause wheel 35, to run in groove 29, with means for holding the wire in proper position to run through slot 33, of guide 31 and means for operating said machine, sub-

stantially as shown and described and for the purposes set forth.

2. In a spooling device, a shaft for carrying the spool; means for driving said shaft; a guide for the material being wound; a cam-shaft, carrying a cam for operating said guide; connection between the spool-shaft and cam-shaft comprising the triple wheel, said wheel consisting of the center wheel *b*, having in its periphery, a row of cogs and on each edge of the wheel, an additional row of cogs, smaller than the central cogs; the cog-wheel *a* on one side and the cog-wheel *c* on the other

side of said wheel *b*; the triple wheel *a'*, *b'* and *c'* on said cam-shaft, the wheel *a* adapted 15 to mesh with wheel *a'*, the wheel *b* with wheel *b'*, and wheel *c* with wheel *c'*; substantially as shown and described and for the purposes set forth.

In testimony whereof I affix my signature 20 in presence of two witnesses.

VILLA WILKERSON.
